OIL WELL EQUIPMENT

Joseph H. McEvoy and James H. Howard,
Houston, Tex., assignors to McEvoy Company,
Houston, Tex., a corporation of Texas

Application July 16, 1938, Serial No. 219,632

10 Claims. (Cl. 166—14)

This invention relates to the art of oil wells and provides certain improvements in oil well equipment, as well as a novel method for handling and completing the installation of oil well equipment. Certain of the novel features of this invention, however, have application beyond the art of oil wells.

One of the primary objects of this invention is to provide novel means and a novel method for completing a well while it is maintained under control so as to prevent a blow-out.

Another object of this invention is to provide improved means for supporting or hanging the tubing and/or casing of oil wells.

Another object is to provide means which support the tubing in a producing well and permit disconnection of the tubing from its support when it is desirable to lower the tubing for performing certain operations in the lower part of the well. It is desirable at certain times in the life of a producing well to unhang its tubing and lower the same in the well, so that the lower tubing end may be used, for example, as a feeler to determine if the screen or perforated pipe has risen from its normal position adjacent the well bottom. It may be also desirable to lower temporarily the tubing for recompressing the packing of the well packer near the well bottom, if the findings of the feeler and the behavior of the well indicate that such is necessary.

A further object is to provide means for hanging and releasing, at will, oil well tubing from its hanger support while the well is maintained under pressure.

Another object is to provide a tubing hanger that will permit a string of tubing connected together with collars to be passed therethrough.

Another object is to provide a hanger for detachably supporting a string of tubing or casing, which hanger will readily pass through auxiliary pressure control attachments which are temporarily mounted on well heads when tubing is being installed in a well or is being removed therefrom.

Another object of the invention is to provide a connection between a well casing or a well tubing and a well head or part thereof to allow the hanging of a string of well casing or of tubing from the well head or from a cooperating part that also fits or is in turn suspended by the well head.

Another object of the invention is to provide a connection between two cooperating parts, such as tubes or rods, which are hollow or solid, and round or polygonal in cross-section so that

tension along the axis of one part will cause means to act and lock the other part against relative rotation, if torque is applied thereto.

Another object is to provide an improved coupling device for the set-shoes of oil well equipment. 5

A further object of this invention is to provide an improved type of coupling device.

Another object is to provide a coupling device for two cooperating parts, such as tubes or rods, 10 hollow or solid, round or polygonal in cross-section, whereby tension or compression in the direction of or along the axis of one member will be imparted to the other member.

Other objects of this invention will be apparent 15 from the following description, the appended claims, and the accompanying drawings, which illustrate preferred embodiments of this invention.

In the drawings,

Figure 1 is a side view, partly in elevation and partly in central longitudinal section, showing oil well equipment embodying this invention.

Figure 2 is a central longitudinal view in section of another embodiment of this invention. 25

Figure 3 is a transverse cross-sectional view taken on line 3—3 of Figure 1.

Figure 4 is a view partly in elevation and partly in cross-section of an oil well and its apparatus including a christmas tree and also means embodying this invention. 30

Figure 5 is a view partly in elevation and partly in longitudinal central section showing a set-shoe embodying this invention.

Figure 6 is an exploded view partly in elevation 35 and partly in cross-section of a coupling device embodying this invention.

Figure 7 is a view partly in elevation and partly in cross-section of another form of the coupling embodying this invention. 40

Figure 8 is an exploded view of still another form of the coupling embodying this invention.

Figure 9 is a cross-sectional view taken on lines 9—9 of Figure 6 and is similar to a view taken on lines 9—9 of either Figures 7 or 8. 45

Referring now to the drawings in detail, Figure 1 shows a casing head 1 which is internally threaded at its lower end for connection with a conventional string of casing. The casing head 1 has a lateral flange 2, and a tapered seat 3. 50 The casing head 1 is also provided with one or more ports 4 through which fluid may be delivered to or from the oil well.

Mounted on the tapered seat 3 is a tapered bushing or hollow hanger body member 5 which 55

is provided with packing rings 6 of any suitable material. These rings 6 form a seal between the tapered end of the hanger body member 5 and the seat 3. The hanger body member 5 is secured to casing head flange 2 by means of the bolts 7 and the flange or ring 8. The flange 8 may be formed integral with the body member 5 or may be a separate ring disposed on the shoulder 9 of the hanger body member 5, as shown in Figure 1.

The body member 5 is formed at its lower end with a shoulder 10. This shoulder 10, if desired, may be provided by a separate ring threaded into the interior of the lower end of body member 5. A packing 11 of any suitable material is supported by the shoulder 10. The packing 11 is preferably a duprene solid ring, but may be formed of rubber, or other elastic material. A ring or gland 12, preferably formed of metal such as steel, is placed on the top of packing ring 11.

Above the metallic ring 12 are two concentrically arranged, cylindrical bushings 13 and 14. The outer bushing 14 has threaded engagement with the interior of the body member 5. The outer bushing 14 is also provided on its inner side with grooves 15 extending vertically from end to end thereof. The inner bushing 13 is formed with splines or feathers 16 on its exterior surface. The bushings 13 and 14 are assembled with the splines 16 received by the grooves 15. This connection between the two bushings 13 and 14 will prevent rotary movement of the inner bushing 13, but permit it to move axially, that is toward or away from ring 12. The adjacent edges of the bushing 13 and ring 12 are preferably tapered so that bushing 13 will be properly centered and seated by the ring 12 (see Figure 1).

The usual tubing of an oil well is to be secured to the internally threaded lower end of a tubular hanger mandrel 20. The preferred proportions of the several parts are such that the hanger mandrel 20 has a close, sliding fit within the lower end 21 of the hanger body member 5, the rings 11 and 12, and the upper portion of the bushing 13. The hanger mandrel 20 is detachably connected to the bushing 13 for hanging the oil well tubing. This detachable connection may be provided by a lefthand acme thread on the outer surface of the hanger mandrel and an acme thread on the inner side of the lower end of the bushing 13. The upper end of the hanger mandrel 20 is internally threaded with threads of righthand pitch to fit righthand pitch threads of handling joint.

A swaged nipple 25 is threaded into the interior of the upper end of the hanger body member 5. The upper end of the nipple 25 is of reduced external diameter and is externally threaded for connection with conventional oil well accessories. The nipple 25, for example, may be provided with the conventional Christmas tree well known to the oil well art. Or the nipple 25 may carry the usual, conventional combination of master control valve and blow-out preventer.

The equipment of this invention is particularly useful with producing, high pressure oil wells which are maintained under control at all times. Normally the tubing supported by the hanger mandrel 20 is hung in a stationary position. That is, the hanger mandrel 20 is hung or arranged in the manner illustrated by Figure 1. In this position of the hanger mandrel 20, the weight of its tubing is carried by the packing 11, which is, therefore, compressed or squeezed in the space between the hanger mandrel 20, the

ring 12 and the hanger body member 5 to provide an efficient sealing means.

When the hanger mandrel 20 is to be unhung, a drill pipe or other suitable tubing handling means (not shown) is passed downwardly through the accessories mounted on the nipple 25 and also through the nipple 25, until its movement is arrested by the hanger mandrel 20. The drill pipe is then rotated until it is completely screwed into the upper, internally threaded end of the hanger mandrel 20. It will be noted that the internal diameter of the nipple 25 is sufficiently large to pass the size of drill pipe which is required for connection with the hanger mandrel 20.

When the drill pipe and hanger mandrel 20 are secured together, continued rotary movement of the drill pipe in the same direction will effect rotary movement of the hanger mandrel 20 relative to the bushing 13, which as previously explained is held against rotation by the bushing 14. This rotary movement of the hanger mandrel 20 will effect its disconnection from the bushing 13, so that the tubing may be lowered by means of the drill pipe. The overall, external diameter of the upper mandrel portion including its external acme thread is preferably somewhat smaller than the external diameter of its lower portion which extends below the acme thread. This relative proportioning will permit the hanger mandrel 20 to pass completely through the rings 12 and 11, and the end 21 of the body member 5 as the tubing is lowered. The lower hanger mandrel portion, that is the portion below the acme thread, is preferably cylindrical and assists in maintaining the acme thread clear of the rings 11 and 12 as the tubing is lowered or raised.

When the tubing is to be again hung, the drill pipe is raised until the acme thread of the bushing 13 rests on the acme thread of the hanger mandrel 20 or until movement of the hanger mandrel 20 is arrested. The drill pipe is then rotated to couple the bushing 13 to the hanger mandrel 20. After hanger mandrel 20 is connected to bushing 13, the tubing is supported on packing 11, thereby relieving the handling joint from its previous tension load so that the handling joint may be easily unscrewed from the righthand pitch thread of hanger mandrel 20. The drill pipe is then backed out until it passes a control valve (not shown), which latter is then closed. The drill pipe may then be completely withdrawn from the well equipment.

The thread on the interior of the upper hanger mandrel end is of the type commonly used for oil well tubing and drill pipe, but the threads on the exterior of the hanger mandrel 20 are of a different type. This construction is provided so that when the tubing is to be lowered the drill pipe or handling joint will be sufficiently screwed into the hanger mandrel 20, before the latter is moved relatively to the bushing 13. The handling joint is preferably raised, after connection with the hanger mandrel 20, to pick up the tubing and relieve the bushing 13 of its load while the hanger mandrel 20 and bushing 13 are being uncoupled, by lefthand rotation of handling joint. The two sets of threads are also such that continued rotary movement of the drill pipe in one direction will couple it to the hanger mandrel 20 and then uncouple the latter from the bushing 13, and that continued rotary movement in the reverse direction, when the tubing is to be hung, will first couple the hanger mandrel 20 to the

bushing 13 and then effect uncoupling between the hanger mandrel 20 and the drill pipe.

The lower end of the hanger body member 5 is tapered at 22 to center and guide the upper end 5 of the hanger body member 20 when the latter is raised into the member 5 during the hanging operation.

The bushing 13 is preferably of such length that its upper end is positioned below the upper 10 end of the hanger mandrel 20 when the two are assembled as in Figure 1. The nipple 25 is also provided with an annular stop surface 26 and an annular shoulder 27. With this arrangement the mandrel 20 will engage the stop surface 26 and 15 prevent engagement of the bushing 13 with the shoulder 27, if the mandrel 20 is raised with the bushing 13 secured thereon as in Figure 1.

The embodiment of Figure 2, except as to details which will now be explained, is substantially 20 the same in construction, and operates in substantially the same manner, as the embodiment of Figure 1. According to Figure 2, the cylindrical bushings 30 and 31, which correspond to bushings 13 and 14 of Figure 1, are so connected 25 that the bushing 31 limits the extent of possible upward movement of the bushing 30. This feature is secured by limiting the grooves 32 in the bushing 31 to the lower portion thereof. The splines or feathers 33 of the bushing 30 by their 30 engagement within the grooves 32 prevent rotation of the bushing 30 and prevent further upward movement of the bushing 30 when they (splines 33) engage the upper end 34 of the grooves 32. It is also to be noted that the bushing 35 30 is materially shorter than the bushing 13 of Figure 1. The embodiment of Figure 2 also omits the nipple shoulder 27 of the Figure 1 construction and provides the tapered surface 35. The packing 37 of Figure 2 also is shown as 40 being formed of a plurality of rings instead of a single ring as in Figure 1.

The bushing 31 may be initially tightened into engagement with ring 12 to maintain packing 37 in place when it is not subjected to the weight 45 of the well tubing.

In the practice of this invention, the tubing hanging and unhangng operation can be performed without removing the conventional Christmas tree or master control valve and blow-out preventer, if such are being used with the 50 present equipment. The present invention therefore, permits hanging and unhangng of the well tubing while the well is held under pressure.

Figure 4 illustrates a well having equipment 55 embodying this invention and shows the tubing in position prior to its being hung. The equipment of the well in Figure 4 includes a surface or short string casing 50, a long string casing 51, and tubing 52 connected by collar 52'. The long 60 string casing 51 is connected to the casing head 1. The casing head 1 is provided with a quick closing plug valve 53 and a blank bull plug 54. The casing head 1 forms part of a Christmas tree which includes a master tubing valve 55, a stuffing box 56, an auxiliary valve 57, a needle valve 58 to control well flow, and a pipe connection 59 which leads to field flow tanks (not shown).

The tubing 52 is carried by the hanger mandrel 20 which is suspended from the handling joint 65 extending through the casing head 1 and stuffing box 56. The handling joint 65 is supported by a conventional swivel and is also connected by hose to mud pumps (not shown). These mud pumps force the mud through the 70 handling joint 65 and the tubing 52 into the well. 75

The mud circulates upwardly within the casing 51 and finds exit through valve 53.

At the lower end of tubing 52 is arranged a packer liner 75, two joints 71 of blank liner, a screen or perforated pipe 72, and a set shoe 73, to which tubing is secured by left-hand thread to facilitate release of tubing. The packer liner 75 includes a packer compression sleeve 70 and packer canvas 74, which, when compressed, forms a seal between liner and casing 51. 10

The bottom of the long string casing 51 is at 15 76, below which the open well hole is plastered with mud. The oil sand strata of the well is indicated at 77.

When it is desirable to hang the tubing 52, the 20 handling joint 65 is raised and operated to secure the hanger mandrel 20 to the bushing 13 (see Figure 1) as previously described. The handling joint 65 is then uncoupled from the hanger mandrel 20 and raised above the master valve 55. 25 This valve 55 is then closed and the handling joint 65 may be backed out of the stuffing box 56 while the well is held under control.

When it is desirable to again lower the tubing 25 65, the handling joint 65 is inserted into the stuffing box 56. The master control valve 55 is next opened to permit the handling joint 65 to be connected to the hanger mandrel 20. During the entire operation for unhangng the tubing 52, the well pressure may be maintained under control. 30

This application describes the invention as applied to the hanging of well tubing. The invention, however, is also applicable to the means for connecting the well screen and liner to the 35 lower end of the string of drill pipe or tubing being used to set the screen and liner in the well bottom and then to release the same.

The set shoe 73, as shown by Figure 5, is also provided with a detachable coupling embodying 40 this invention. The set shoe 73 comprises a shell or body member 90, a cylindrical bushing 91, and a tubular male member 92. The bushing 91 is splined to the body member 90 by means of splines on the exterior of the bushing and grooves 45 on the interior of the body member 90. This spline connection prevents relative rotary movement of the bushing 91 and member 90 but permits relative longitudinal or axial movement. The male member 92 is externally threaded for 50 engagement with the internally threaded bushing 91. These threads are preferably acme threads of left-hand pitch. The bushing 91 is yieldingly urged against a ring 93, which is threaded into the body member 90, by a helical 55 spring 94. This spring 94 encircles the male member 92, is spaced therefrom, and is arranged between bushing 91 and a ring 95 which rests on shoulder 96 of the body member 90. The tubular element or member 92 has an annular 60 shoulder normally in longitudinal engagement with the upper end of the female portion of the set shoe, as shown in Figure 5, whereby the tubular member 92 and the female member are normally disengageable by relative rotational 65 movement.

Figures 6 and 9 show another embodiment of the coupling device. This coupling device comprises a body member 100 to which is splined a nut or bushing 101. The nut or bushing 101 is 70 internally threaded for connection with a similarly threaded male member 102. The body member 100 has a shoulder 103 against which the nut 101 may abut.

In Figure 7 the nut 101 is arranged between 75

an annular shoulder 104 and removable ring 106 positioned within the body 105. The spring 107 which is interposed between the shoulder 104 and nut 101 yieldingly urges the latter toward the ring 106.

5 A modified tubing hanger is shown in Figure 8. The body member 110 is tapered to seat in a tapered well head, has an annular internal shoulder 111 and a removable ring 112. A nut 101 is splined to the body member and is yieldingly urged toward the ring 112 by the spring 113. A pipe member or tubing 114, at one end, is externally threaded for connection with the nut 101 and is internally threaded for connection 15 with a threaded rod 115.

10 The foregoing is illustrative, and it will be understood that this invention includes all embodiments and modifications of this invention coming within the scope of the appended claims.

20 We claim:

1. In well equipment, the combination comprising a hollow hanger body member having an inwardly extending shoulder, packing supported on said shoulder, a ring carried on the top of said 25 packing, a bushing supported by said ring, a tubing hanger mandrel having threaded connection with said bushing to support the entire load of the mandrel, and a second bushing secured to said body member and splined to the outer side of said 30 first-mentioned bushing to prevent rotation thereof during rotation of said mandrel, said mandrel being rotatable to effect disconnection with said first-mentioned bushing and adapted to be then lowered through said body member, 35 packing and ring.

2. In well equipment, the combination comprising a casing head having a tapered seat, a hollow hanger body member disposed on said seat and having an inwardly extending shoulder, packing supported on said shoulder, a ring carried on the top of said packing, a bushing supported by said ring, a tubing hanger mandrel having threaded connection with said bushing to support the entire load of the mandrel, and a second 40 bushing secured to said body member and splined to the outer side of said first-mentioned bushing to prevent rotation thereof during rotation of said mandrel, said mandrel being rotatable to effect disconnection with said first-mentioned bushing and adapted to be then lowered through said body member, packing and ring.

45 3. In well equipment, the combination comprising a hollow hanger body member having an inwardly extending shoulder, packing supported on said shoulder, a bushing supported by said packing, a tubing hanger mandrel having threaded connection with said bushing to support the entire load of the mandrel, and a second bushing secured to said body member and splined to the outer side of said first-mentioned bushing to prevent rotation thereof during rotation of said mandrel, said mandrel being movable relative to said first-mentioned bushing to effect disconnection therefrom and adapted to be then lowered through said body member, packing and ring.

50 4. In well equipment, the combination comprising a casing head having a tapered seat, a hollow hanger body member disposed on said seat and having an inwardly extending shoulder, packing supported on said shoulder, a bushing supported by said packing, a tubing hanger mandrel having threaded connection with said bushing to support the entire load of the mandrel, and 55

a second bushing secured to said body member and splined to the outer side of said first-mentioned bushing to prevent rotation thereof during rotation of said mandrel, said mandrel being rotatable to effect disconnection with said first-mentioned bushing and adapted to be then lowered through said body member, packing and ring.

60 5. In well equipment, the combination comprising a hollow hanger body member having an inwardly extending annular shoulder, annular packing supported by said shoulder, a bushing supported by said packing and mounted for axial movement, means for engaging said bushing to prevent relative rotation thereof, and a hanger mandrel for well tubing, said hanger mandrel extending through said annular packing and being supported by detachable connection with said bushing to hang said tubing, said bushing being adapted to place the load of said supported 65 hanger mandrel on said packing to effect a seal about said hanger mandrel, said hanger mandrel being rotatable relative to said bushing to effect disconnection therefrom and being adapted upon disconnection from said bushing to be lowered 70 through said bushing, said packing and said body member, said hanger mandrel being adapted to be connected with said bushing by being raised through said packing into said bushing and by being rotated relative to said bushing.

75 6. In well equipment, the combination comprising a hollow hanger body member having an inwardly extending annular shoulder, annular packing supported by said shoulder, a bushing supported by said packing and mounted for axial movement, a second bushing secured to said body member and splined to said first-mentioned bushing to prevent relative rotation thereof, and a hanger mandrel for well tubing, said hanger mandrel extending through said annular packing and being supported by detachable connection with said first-mentioned bushing to hang said tubing, said first-mentioned bushing being adapted to place the load of said supported hanger mandrel on said packing to effect a seal about said hanger mandrel, said hanger mandrel being rotatable relative to said first-mentioned bushing to effect disconnection therefrom and connection therewith, said hanger mandrel upon disconnection from said first-mentioned bushing being adapted to be lowered through said first-mentioned bushing, said packing, and said body member.

80 7. In well equipment, the combination comprising a well head having a tapered seat, a hollow hanger body member disposed on said seat and having an inwardly extending shoulder, packing supported on said shoulder, a bushing supported by said packing, a tubing hanger mandrel having detachable connection with said bushing to support the entire load of the mandrel, spline means between said body member and said bushing to prevent rotation thereof during rotation of said mandrel, said mandrel being rotatable relative to said bushing to effect connection or disconnection therefrom and adapted to be lowered or raised through said body member and packing to position said hanger mandrel for connection or disconnection with said bushing.

85 8. In well equipment, the combination comprising a casing head having a tapered seat, a hollow hanger body member disposed on said seat and having an inwardly extending shoulder, packing supported on said shoulder, a bushing supported 90

- by said packing, a tubing hanger mandrel having detachable connection with said bushing to support the entire load of the mandrel, spline means connected to said body member and the outer side of the said bushing to prevent rotation thereof during rotation of said mandrel, said mandrel being rotatable to effect disconnection with said bushing and adapted to be then lowered through said body member, packing and bushing.
10. 9. A set shoe for oil wells, said set shoe comprising a hollow member having an opening in its upper end, substantially annular upper and lower abutments arranged in said body member, an internally threaded element being mounted 15 in said body for movement between said abutments and being normally in engagement with said upper abutment, spring means interposed between said lower abutment and said internally threaded element, and a tubular element normally extending through said opening and having detachable engagement 20 with said connection element, said tubular element having a shoulder normally in longitudinal engagement with said upper end of said hollow member and being disengageable from said hollow member and connection element by rotational movement relative thereto.
15. 10. A set shoe for oil wells, said set shoe comprising a hollow member having an opening in its upper end, substantially annular upper and lower abutments arranged in said body member, a connection element being mounted in said body for movement between said abutments and being 10 normally in engagement with said upper abutment, spring means interposed between said lower abutment and said connection element, and a tubular element normally extending through said opening and having detachable engagement 15 with said connection element, said tubular element having a shoulder normally in longitudinal engagement with said upper end of said hollow member and being disengageable from said hollow member and connection element by rotation- 20 al movement relative thereto.
20. 11. A set shoe for oil wells, said set shoe comprising a hollow member having an opening in its upper end, substantially annular upper and lower abutments arranged in said body member, a connection element being mounted in said body for movement between said abutments and being 10 normally in engagement with said upper abutment, spring means interposed between said lower abutment and said connection element, and a tubular element normally extending through said opening and having detachable engagement 15 with said connection element, said tubular element having a shoulder normally in longitudinal engagement with said upper end of said hollow member and being disengageable from said hollow member and connection element by rotation- 20 al movement relative thereto.
